William P. Bragton New York

Letters Patent.

The device referred to in these Letters Patent, and making part of the same, containing a description in the words of the said Wm P. Bragton, of his "Improvement in the Machine for spinning and doubling cotton."

To all to whom these presents shall come.

Be it known that I, Wm P. Bragton of the City, County and State of New York Engineer, have invented a new and useful improvement in machinery for spinning and doubling cotton silk and other fibrous materials or, in short, fibers, and which are applicable to various useful purposes, and that the following is a full and exact description of the construction and operation of the said improvement as invented by me, reference being had to the drawings hereto annexed and making part of this specification. For the more clearly illustrating these improvements, I have herunto annexed several drawings exhibiting the complete Throstle frame in different positions, with the rotation of the eight driving drums and of the bobbins and flyers, and the manner in which they are activated, and also a mode of dividing flyers and spindles with a side or horizontal cylinder where but one motion is required from the driving drum to the spindles or flyers in consequence of a peculiar way of connecting the machine and of putting on the bands as will be shown in drawing first figured and so on. Drawing No. 1 in this figure, I show an end view of a Throstle frame for spinning, but or horizontal cylinder for driving spindles and flyers. I show an end view

270

view of the cylinders and a view of the bands and also two spindles driven by the same which construction of spindles I claim as the result of my own invention.

A. A. is the Throttle frame b. b. the cylinder, C. the shaft of the cylinder, d. is a metal band that drives two spindles e. e. are the spindles, f. f. are studs that give standing to them spindles, g. g. are stationary rails which the bands h. h. are mounted fast to, h. h. are flyers which are secured onto the top of the spindles to give twist to the thread as it comes from the moving rollers in the usual way. i. i. are the bobbins that receive the thread from the flyers, j. j. are the lifting rails which cause the bobbins to rise and fall for the distribution of the thread upon the bobbins. K. K. are stationary rails for holding the machine together and also receive the foldings of the spindles. L. L. are also stationary rails for holding the machine together. Fig. 3. Shows figure of show a top view of the cylinder and the wheels of the spindles, and also a view of the bands as they will appear when running, some of the spindles are left unnumbered that it may be the better seen how the bands appear on those that are numbered. The letters b. b. denoting the cylinder, C. the shaft, and d. an ordinary band as in fig. 1. Hh. Hh. are the two first spindles upon that side of the machine in order to band spindles Hh. upon the right, I place a friction pulley H. on the left and carry the band around it and over the top of the drum at C. and down at from the under side of the drum as shown in broken lines and up at f. and over the top of the drum again, and around the spindle at H. and then I carry it over the top of the drum again to the friction pulley and tied to the other end of the band at f. at the latter end of the machine so that the band could receive the drive of the spindle at H. and that the top of the drum is drawn upon under the bottom of the drum and kept at D. and over the

The top of of the drum against which are placed a friction pulley at 10 and back to 5 and 10. These friction pulleys being placed the space of one spindle to the right or left for the purpose of banding the first or last spindle by. Many distance would perhaps answer, and the spindles might be so placed in the machine as to need no friction pulleys but this is
conceive to be the best way. It will be perceived that in banding spindles 1/4 width they vary one space from being directly opposite to each other. This is to prevent the bands from running together over the top of the drum in running off. At first I have a full space of spindle might be allowed, but much depends on the width of the machine and the distance the spindles are set apart. Variations enough should be made so that the bands will not run together over the top of the drum. In this way the rolls may be made two feet wide and have cylinders in them for cotton or cotton in diameter.

The top of the cylinder in a machine two feet wide or should be at about one and a half inches below the wheels on the spindles. See drawing 3rd Figure 2 The spindle 1 is represented with a sleeve upon it which fits fast upon the spindle and carries the bobbin 2. This spindle is made to revolve by a band from the driving drum passed round the wheel 3. upon the spindle 1 tube 4 is affixed by its socket and secured to the upper stationary rail except the upper part being bushed to give it a drift with little friction to the spindle which revolves within it and is caused to slide up and down by the movement of the carrying rail. On the outside of the tube 4 another tube 5 is fitted carrying the flyers 6-6 and which last mentioned tube with the flyers are made to revolve by a band from the driving drum passed round the wheel 7 hence it

it will be perceived that the bobbins and the flyers may be made to revolve by one driving discs at dissimilar speeds according to the different diameters of the wheels, and in this instance the spindles should run so much faster ^{than the}飞轮 as to cause the bobbin to lead the flyer to take the yarn up and just keep the thread straight as it is delivered from the dehairing rollers. By driving the flyers with a speed nearly equal to that of the spindles and bobbins the thread will be tempered and yarn of very high numbers may be readily spun and wound upon the bobbins. Drawing 9^{1/2}. Fig 1 shows front elevation of the Throttle frame constructed on an improved plan with a series of bobbins and flyers driven by upright wheels or cylinders. Fig 2 is a transverse section of the same showing the manner in which the driving bands pass from the upright drums to the wheels of the spindles and flyers. Fig 3 is the elevation of the Throttle frame taken at that end where the driving pulleys or ridders is afficed. Fig 4 is an elevation of the reverse end of the Throttle frame showing the bands and pulleys by which the upright drums are driven; the similar letters of reference pointing out what the same parts in the four last mentioned figures. The end frames or standards of the Throttle are shown at a, a. Fig 5. and b, b. is the middle frame c, c, c, c, are the longitudinal stationary rails by which the end and middle frames are braced together and the principle parts of the machine supported d, d. Fig 6. are the fast and loose pulleys or ridders over which a strap is passed from the first moving power to drive the machinery. e is the main shaft or axle communicating motion to the working parts of the machine and f is a flywheel and pulley affixed to the end of the main driving shaft to work which pulley or wheel turns

bound up paper over diagonal guide pulleys $b-b$ and mounted the grooves at the upper part of the upright $c-c$ for the purpose of giving rotary motion to the driving drums. These drums d are turned upon vertical $e-e$ and bearing in $t-t$, are passed round the respective wheels of the spindles $f-f$, and round the drums d and similar bands $g-g$ are passed round the respective wheels of the flyers and also round the drums by which means when the drums are set in motion, and made to revolve by the manner before described. The spindles and flyers will be driven round as the spindles revolve and describe their driving bands more up and down upon the periphery of the driving drums, always presenting the same altitude as the wheels and thereby keeping the bands at all times at the same strain or tension. One side of the machine is made higher than the other in order that the bands of the spindles upon one side of the machine shall all pass round the drums above the bands of the spindles upon the other side of the machine and not interfere with each other and the same is to be observed in respect to the bands which carry the flyers as shown in Fig 2 which constitutes a part of this invention.

The bottom or other materials to be spun to be placed on the top of the machine in the usual manner, and 2 large stones to support them. W.W. in Fig 3 are drawing rollers $s-s$ which being so constructed as to allow a rod to be placed longitudinally in the back side of the stand at $x-x$ in order that the weight that causes the top or drawing rollers to press upon the bottom ones may pull equal to the weight of the bottom drawing rollers so that the rollers may be elevated or turned up so as to allow the twist of the thread or yarn to run up immediately into the jaws of the rollers, that the article

to be spun may receive the twist as soon as the diamond
rollers leave it, which is found to be extremely necessary
when spindles are run at very high speed and more
particularly in the spinning of fine yarns. The wire
that is attached to the weight of Fig. 2 and the wire on
which it hangs and longitudinal rail or cap rails may
be substituted and supported at each end by the bottom longi-
tudinal stationary rail and in this case the axles may
be driven by motor or belt wheels, for which invention
no claim is made for spinning novelties in the dock or bottom fly
frames for which this principle of driving is also claimed.
Axle driving would perhaps be most suitable, and the
spindles or shafts of the axles are confined in bollards
in a longitudinal rail at the top as shown in Fig. 2. The pine
deck of a carriage arranged in series on each side of the frame
supported in steps at the bottom by the capping rail A. B.
and passed through tubes and sockets in the upper stationary
or longitudinal rail C. C. The bobbins being upon a disc
mounted upon the upper part of the spindles and turning
therewith. The flyers are attached to a tube as before de-
scribed with a wheel affixed to the flyers tube the capping
rails A. B. supporting the spindles are made to rise & fall
for the purpose of winding the yarn in uniform coils on
upon the bobbins by the ordinary contrivance, that is
to say by connecting these rails to pendant chains b. b.
attached to longitudinal shafts on - on - which reach the
whole length of the machine. Another chain H. Fig. 3 is
attached to a pulley D. on shaft H. and made fast at the
lower end to the lever F. which lever is mounted on a
slide set in a transverse carriage rail G. and is made to
vibrate by the rotation of the last wheel of a board
and balance weight being attached to the second end
of the lever. These two lifting rods H. M. Fig. 3 are connected
by

by a chain of transversely, as shown in Fig 3, and the spindles are lifted upon both sides of the machine at the same time, with the same power that would be required to lift one side providing the weight attached to the lever are sufficiently heavy. In order to drive the spindles and flyers bands attached to the saddle of the top drawing rollers are connected by a connecting rod bearing over the saddle or a small pulley upon the bar Z Z are guide wires between the back and middle drawing rollers attached to the traversing rod for the purpose of keeping double rollers together and never cause them to break, which is a great convenience in spinning fine yarns both in the Throttle and the mill. These guide wires and the above mentioned band will also constitute a part of this invention. This Throttle is especially adapted to the spinning of fine yarns.

By causing the spindles to carry the bobbins, the drag is taken off of the thread as it comes from the flyers which puts it in the truest and very light condition may be spun off the spindle running within the bobbin, and the disc which the bobbin rests upon being fast to the spindle and revolving therewith a fine surface is produced under the bottom of the bobbin and also inside of the bobbin, so that the drag upon the thread may be nicely tempered that a pair of the hundred bobbins to the pound may be readily spun.

By placing the wheels of six spindles and six flyers which constitute a set to be run upon one side of a door at different heights the bands will run clear of each other as shown in Fig 4. In drawing 15. I am enabled to put a 10 or 12 inch cylinder into a Throttle frame that is only two feet wide, whereas Throttle frames are now made four feet wide, to receive a cylinder only seven inches

inches in diameter, which cylinder must revolve as fast as mine to give the same speed to the spindles and at the same time is not able to stand as high speed as a larger cylinder, and by having a small cylinder, the whole on the spindles are often made small in order to get the necessary speed, which is very destructive to the spindles by being obliged to have the bands much tighter, by having a large cylinder, I am enabled to have the whirs and spindles larger and consequently enabled to turn spindles with a slackened band, and again by putting the band all around the cylinder, it gives the cylinder more power upon the band and the band will bear to be slacken on that account and the slacken the band is him the better it will last, and the longer the spindles will last, and again the bands in this way run straight upon one side of the whirs of the spindles and upon the other side, have an angle of only an inch and a half to the front.

What I claim as my invention is the method of banding and driving the spindles substantially as is described in the above specification and referred to in drawing 1st Fig 17 & thereby covering one half of the room in the width of the Throstle frame, and being enabled to use a large cylinder instead of a small one which is in all cases desirable; I also claim the spindles substantially as described above and referred to in Fig 1st drawing 1st. I also claim the peculiar construction of the parts of a Throstle frame for spinning and doubling substantially as is described above and referred to in drawing 2nd.

I also claim the adaptation of copyright down cylinders for driving the spindles and the flyers by distinct bands in a Throstle frame substantially as

959 1925
277.
as is above described and also the peculiar modes
of mounting and drawing the bobbins and the flyers
in a Throstle form for the purpose of causing them
to revolve with distinct and dissimilar speeds
substantially as is described above, and I also
claim the stand and the guide wires substantially
as is above described.
